UNITED STATES PATENT OFFICE.

CLARENCE E. BEACH AND LEE J. VOORHEES, OF BINGHAMTON, NEW YORK, ASSIGNEES,
BY MESNE ASSIGNMENTS, TO THE GAMEWELL FIRE ALARM TELEGRAPH COMPANY,
A CORPORATION OF NEW YORK.

SIGNAL-BOX.

1,205,319.

Specification of Letters Patent. Patented Nov. 21, 1916.

Application filed February 23, 1915. Serial No. 9,991.

To all whom it may concern:

Be it known that we, CLARENCE E. BEACH and LEE J. VOORHEES, citizens of the United States, residing at Binghamton, in the county 5 of Broome and State of New York, have invented certain new and useful Improvements in Signal-Boxes, of which the following is a specification.

Our invention relates to signal boxes having a manual starting or operating handle by means of which they may be set in motion and the driving power for the clock-work employed therein may be wound.

Our invention relates to signal boxes having a so-called "local noninterference pull" whereby the operation of the starting member both winds the clockwork and conditions it for operation, so that the manipulation of the starting member after the clock work 20 has been wound and conditioned for operation will not affect the operation of the signaling train.

The objects of this invention are to enable signaling boxes of the type described to be 25 more economically manufactured, to render said boxes more reliable and efficient in operation, and to attain the new results hereinafter described and more fully pointed out in the claims.

With these and other objects in view, this invention consists in certain novel constructions and arrangements of parts shown in the drawings accompanying and forming part of this application, described in the 35 following specifications, and more particularly pointed out in the claims.

Like characters of reference denote the same parts throughout the accompanying drawings, in which—

40 Figure 1 is a front view of a signal box embodying this invention; Fig. 2 is a view showing the outer door open, and exposing the operating handle mounted upon the inner door; Fig. 3 shows the signal box of Figs. 1 and 2 with both doors open; Fig. 4 is a front elevation of the signaling train of the box shown in Fig. 3 removed from the case; Fig. 5 is a rear elevation of the signaling train shown in Fig. 4; and Fig. 6 is a 45 sectional side elevation of the signaling mechanism mounted upon the inner door 50

taken on the lines 6—6 of Figs. 2, 4 and 5. Fig. 7 is a fragmentary detail to be referred to.

Referring to Fig. 2, 11 is the outer door, 55 hinged to the case at 12, and provided with a spring latch 13 adapted to engage with the notched stud 14, mounted upon the inner door 15, so as to yieldingly retain the outer door in closed position.

The recessed head 16 is suitably formed upon or connected to the screw 17 carried by the door 12 (see also Fig. 3), said head being adapted to receive a suitable key for turning said screw, the free end of said screw being 60 adapted to enter the opening 18 in the back of the case 19 for the purpose of firmly holding the door 15 in closed position.

The operating handle 20 is fixed upon the shaft 21 and is so formed as to be readily 70 manipulated. The shaft 21 passes through the door 15, and the front plate 22 and back plate 23 which form part of the signaling train, comprising the motor spring 24 which is connected to the main shaft 25 which carries the ratchet 26 and main gear 27 for driving the shaft 28 carrying the wheel 29 which drives the escape wheel 30 whose movement is regulated by the escapement pallet 31. A restoring spring 32 is so 75 applied to the shaft 21 as to tend to turn said shaft in the direction which will raise the operating handle 20. A ratchet is provided for resisting the movement of said shaft 21 in response to the spring 32, comprising 80 the ratchet wheel 33 and the pawl 34 adapted to engage therewith. A detent arm 35 is loosely pivoted upon the shaft 21 and carries near its free end the detent pin or projection 36 which is adapted to engage with 85 the escape wheel 30, a suitable spring 37 being so connected to the arm 35 as to tend to swing said arm to carry the pin 36 into engagement with the wheel 30.

The detent arm 35 is so connected with the 95 shaft 21 that said arm will be moved to carry the pin 36 out of the path of the escape wheel 30 when such shaft is rotated to a certain position, said connection consisting of the boss 38 which is loosely pivoted upon 100 the shaft 21 and to which the arm 35 is fixed, said boss having a slot 39 formed therein in

2
suitable relation to the pin 40 carried by the shaft 21.

Suitable winding mechanism for the motor spring 24 is provided, consisting of 5 the pinion 41 fixed upon the shaft 25, and the sector 42 pivoted at 43 and adapted to coöperate with said pinion 41. A follower arm 44 is pivoted at 43 and is adapted to move independently of the sector 42 and is 10 adapted to suitably engage said sector so that it may drive said sector in one direction. The collar 45 is secured to the shaft 43 and provides an outboard bearing for the follower arm 44 and acts as a stop as 15 hereinafter more fully explained. For convenience and economy in manufacture, a tongue 42^a may be formed in the sector 42 in such position as to be adapted to be engaged by the follower arm 44. The spring 20 46 is so applied to the follower arm 44 as to tend to hold said arm against the tongue 42^a.

The follower 47 consists of a roller mounted in the path of the cam 48 and 25 adapted to suitably coöperate with said cam. The cam 48 is provided with a winding face 49, a holding face 50, and a deflecting face 51, said faces being so formed that when 30 the train is unwound, the follower 47 will lie in the path of the winding face 49, and thereupon if the shaft 21 is rotated by depressing the operating handle 20, said winding face 49 will impart such motion to the follower 47 as will swing the sector 42 in 35 engagement with the pinion 41 and thereby suitably wind the motor spring 24.

A connection is provided for disengaging the pawl 34 from the ratchet wheel 33 when the signaling train is unwound, consisting 40 of the extension 52 carried by the sector 42. The teeth of the ratchet wheel 33 are so spaced in relation to the movement imparted to the shaft 25 by the rotation of the shaft 21 that one of said teeth will be 45 engaged by the pawl 34 just prior to or at the time that each tooth of the ratchet 26 is engaged by the pawl associated therewith, so that if the operating handle 20 is depressed for less than its entire travel, it 50 cannot be left in a position where upon subsequent operation it will be permitted to move a substantial distance opposed only by the restoring spring 32 and then be brought into engagement with the follower 55 47, and thereby mislead the operator into believing that the initial movement had wound the train and that the handle had reached its limiting stop.

The length of the winding face 49 is such 60 as to be adapted to drive the follower 47 far enough to carry the ratchet 26 a substantial fraction of a tooth more than the desired number of teeth, for the double purpose of assuring a margin in movement 65 so that the train will always be sufficiently

wound, and for permitting the motor spring 24 to raise the sector 42 far enough after the winding face 49 has disengaged the follower 47 so that said follower will pass above the holding face 50, and thereby retain the operating handle 20 in its depressed position during the entire running of the train and thereby give a visual indication that the train has been set in motion.

The holding face 50 is of such length as 75 to enable the follower 47 to hold the cam 48 in depressed position until the signaling train has completed the desired movement, whereupon the extension 52 will disengage the pawl 34 from the ratchet wheel 33, and 80 the cam 48 will be restored to the position shown in Fig. 4 by the restoring spring 32, the deflecting face 51 being of such length as to sufficiently raise the follower 47, against the tension of the spring 46 during 85 such restoration of the cam 48, so that after said follower has passed the junction of the faces 49 and 51, the follower arm 44 will have been raised a sufficient distance above 90 the tongue 42^a so that when returned into engagement with said tongue by the spring 46, the follower 47 will be brought safely under the winding face 49.

The signal wheel 53 is carried by the shaft 28 and is arranged to suitably influence 95 the signaling lever 54 which in turn suitably controls the contacts 55 and 56 which are mounted upon the insulating block 57.

The terminal strips 58 and 59 are clamped 100 against the springs 55 and 56, respectively, by means of the attaching screws 60—60 and 61—61 respectively. The contact spring 56 and terminal strip 59 are provided with a clearance hole for each attaching screw 60 105 through which the head of said screw may freely pass, and a suitable recess is provided in the insulating block 57 so as to permit the head of each screw to be sunk far enough below the plane of the contact 110 spring 56 to provide a suitable clearance, a suitable number of screws being employed, which pass through the contact spring 55 and are screwed into the terminal strip 58, similar provisions preferably being made 115 for suitable attaching screw or screws 61, so that the insulating block need not be tapped, and may be constructed of comparatively brittle material as the strain applied thereto by these screws is only a clamping 120 strain, and the contact springs and terminal strips are both held rigidly in position and highly insulated from each other. It is evident that, if desired, these clearance holes need only be provided in one contact spring 125 and its associated terminal strip, it then being merely necessary to first attach the contact spring and strip having the clearance holes. If it is desired to employ an insulating block having suitable recesses for 130

the contact springs, but one attaching screw for each contact spring need be used, and it is further evident that, if desired, the terminal strips may be omitted and suitable nuts used in place thereof.

A crank 62 is carried by the shaft 63 and is provided with an insulating covering 64, adapted when swung in one direction to lift the contact spring 56 out of engagement with the contact spring 55, and when swung in the opposite direction to hold the contact spring 55 in engagement with the contact spring 56.

A stop pin 65 is fixed in the plate 23 in the path of a projection 66 moving with the shaft 63 so as to suitably limit the movement of the crank 62.

The recessed head 67 (see Figs. 2 and 4) is carried by the shaft 63, and the door 15 has a hole so that such shaft may be suitably rotated by inserting a proper key through said hole in the door and into the recess in the head.

The shield 68 is provided around the signaling train for protecting said train from interference from the connecting wires leading to the terminal strips 58 and 59.

A limiting arm or detent 69 is carried by the shaft 25 and is adapted to be carried in the path of the limiting pin 70 when the train is unwound, so as to assure the stopping of the train at a proper point even if the detent pin 36 is held out of the path of the escape wheel 30 by manually retaining the operating handle 20 in depressed position after the box has completed the transmission of its signal. The operation of this box is as follows: When in normal position, the parts stand as shown in Figs. 2, 4 and 5, except that the door 11 should be kept normally closed to suitably protect the operating handle 20. When it is desired to transmit a signal, the door 11 is opened and the operating handle 20 is grasped and depressed, thereby carrying with it the shaft 21 and cam 48, the winding face 49 of which cam is thus forced against the follower 47, thereby carrying the follower arm 44 and sector 42 downward and turning the shaft 25 so as to suitably wind the motor spring 24. As the operating handle 20 is thus depressed, the ratchet 26 and pawl 34 each act at about the same time, or in any event the pawl 34 acts no later than the ratchet 26, so that if the operating handle is not depressed for a sufficient distance to start the train, it will be left standing in a position from which its downward movement will be opposed by the force of the motor spring 24. If the operating handle 20 is depressed as far as it will go, the winding face 49 will be brought into engagement with the collar 45 and said winding face 49 will be withdrawn from the path of the follower 47 whereupon the back lash of the ratchet 26

and the signaling train will permit the motor spring 24 to slightly raise the sector 42 and thus carry the follower 47 in the path of the holding face 50. Such rotation of the shaft 21 as will withdraw the winding face 49 from the path of the follower 47 will also swing the detent arm 35 against the tendency of the spring 37 so as to carry the detent pin 34 out of the path of the escape wheel 30, and the signaling train will thereupon operate and cause the intended makes and breaks in a circuit connected to the terminal strips 58 and 59 in a well known manner. The follower 47 will be carried along the holding face 50 as the signaling train operates, and just before the completion of the intended operation of the signaling train, said follower will be carried to the left of said holding face (see Fig. 4). When the follower 47 has been thus carried to the left of the holding face 50, a slight additional operation of the train will carry the sector 42 high enough to cause the extension 52 to carry the pawl 34 out of engagement with the ratchet wheel 33 and thus permit the shaft 21 to be restored to normal position by the spring 32. If such restoration of the shaft 21 is prevented by holding the operating handle 20 in depressed position after the pawl 34 has been thus disengaged, the train can move but a short distance farther as the pin 70 will be carried into engagement with the limiting arm 69 which is carried into the path of said pin when the signaling train has completed its intended operation. Upon the disengagement of the pawl 34 from the ratchet wheel 33, the shaft 21 will be rotated to its normal position by means of the spring 32 unless manually restrained (as just described), and such rotation will cause the deflecting face 51 of the cam 48 to engage the follower 47 and raise the follower arm 44 a short distance above the tongue 42^a, but, upon the completion of such return movement of the shaft 21, the deflecting face 50 will be carried out of the path of the follower 47 whereupon the arm 44 will be swung into contact with the tongue 42^a by the spring 46 and thus carry the follower 47 into the path of the winding face 49. If it is desired to operate the contacts 55 and 56 without operating the signal train, the shaft 63 may be so rotated by inserting a suitable key in the recessed head 67 as to bring the insulating covering 64 into engagement with the contact 56 and lift said contact out of engagement with the contact 55. If it is desired to operate the signaling train without operatively affecting the signaling contacts 55 and 56, the shaft 63 should be rotated in the opposite direction, so as to hold the contact 55 independently of the signaling lever 54, and while so held the signaling train may be operated and the contact 55 will re-

main in engagement with the contact 56. In either event, when released the shaft 63 will be returned to normal position, as shown in Fig. 5, through the action of the 55 spring 71.

What we claim is:

1. In a signal-box, a windable signaling train, an operating handle for said train adapted to be manually operated in one direction to wind the train, a plurality of engaging means adapted for successive operation as the handle is moved into wound position for retaining said handle against movement in the opposite direction in intermediate positions as well as in wound position, said engaging means being arranged to be operated by a part moving with the train to release said handle when the train is unwound, and a spring for restoring the handle 20 when released.
2. In a signal-box, a windable signaling train, a winding-member for the train, a manually operable cam coacting with said winding-member having a winding-face and 25 a holding-face, the winding-face engaging and moving the winding-member during manual operation of the cam to wind the train, and the winding-member moving over the holding-face and holding the cam while 30 the train is running to send its signal, and disengaging said holding-face when the signal is sent to admit of restoration of the cam and of the passing of the winding-member into engagement with the winding- 35 face.
3. In a signal-box, a windable signaling train, a pivoted sector engaging the winding-shaft, a winding-arm independent of but adapted for engagement with said sector, a 40 manually operable cam coacting with said winding-arm, having a winding-face and a holding-face, the winding-face moving the winding-member to wind the train, and the winding-arm passing over the holding-face 45 while the train is running and the signal is being sent, to hold said cam against return movement, said cam having means for moving said winding-arm independently of the sector to cause it to pass onto the winding- 50 face when the signal is sent.
4. In a signal-box, a windable signaling train, a pivoted sector engaging the winding-shaft, a winding arm independent of but normally held in engagement with said sec- 55 tor by a spring, a manually operable cam coacting with said winding-arm having a winding-face, a holding-face, and a deflecting-face, the winding-face engaging and moving the winding-arm during manual op- 60 eration of the cam to wind the train, and the winding-arm moving over the holding-face and holding the cam while the train is running to send its signal and disengaging said holding-face when the signal is sent, 65 and the deflecting-face engaging the wind-

ing-arm as the cam is being restored to lift said arm and permit it to pass from the deflecting-face onto the winding face.

5. In a signal-box, a windable signaling train, a winding-member for the train, a manually operable cam coacting with said winding-member having a winding-face, a holding-face, and a deflecting face, the winding-face adapted to engage and move the winding-member during manual operation 75 of the cam to wind the train, the winding-member moving over the holding-face to hold the cam while the train is running to send its signal, and the deflecting-face engaging the winding-member and releasing 80 it while the cam is being restored to admit of said winding-member passing onto the winding-face when disengaged from the deflecting-face.

6. In a signal-box, a windable signaling 85 train, an operating handle adapted to be manually operated in one direction to wind the train, means for holding it in wound position while the signal is being sent and for releasing it at the end of the signal, 90 means for automatically restoring it when released, and two detents for the train, one of said detents being controlled by the train in running and arranged to become effective whenever the train has run down to a pre- 95 determined point, and the other of said detents being controlled by the handle and arranged to become effective when the handle is in restored position, and to remain effective while the handle is being moved 100 manually into wound position.

7. In a signal box, a windable signaling train, an operating handle adapted to be manually operated in one direction, means for automatically restoring said handle after 10 manual operation thereof, retaining means controlled by said train and adapted to hold said handle against restoration except when said train is unwound, a cam moving with said operating handle, a winding member 11 for said train adapted to suitably coöperate with said cam, and two detents for said train one of said detents being arranged to become effective whenever said train has run down to a predetermined point and the 11 other of said detents being arranged to become effective when the operating handle is in restored position and to remain effective during a suitable portion of the operation of the operating handle.

8. In a signal box, a windable signaling train, an operating handle for said train adapted to be manually operated in one direction, means for automatically moving said handle in the opposite direction, a follower mounted upon a suitable follower arm, a winding sector for said train having a tongue formed therein projecting in the path of said follower arm, a yielding connection between said sector and said fol- 12 13

- lower arm constantly tending to hold said arm against said tongue, and a cam moving with said operating handle so formed that when moved in one direction it is adapted 5 to so act upon the follower as to force the follower arm against the tongue of the sector and thereby wind the train, to be held against restoration during the unwinding of said train, and to so act upon said follower as to carry the follower arm a suitable distance from said tongue during the restoration of the operating handle so that said yielding connection may condition the follower to be again acted upon by said cam 10 upon the complete restoration of said cam.
9. In a signaling mechanism, an insulating block having attaching screw holes therein, signaling contacts mounted upon the opposite sides of said block, and attaching screws for said contacts, each of said contacts having a clearance opening therein for the head of each attaching screw for the other contact.
10. In a signaling mechanism, an insulating block adapted to have signaling contacts attached to the opposite sides thereof and having clearance holes therein to receive attaching screws for said contacts counter-bored so that the heads of said screws will 25 not project outside the surface of said block, signaling contacts adapted to be mounted upon said opposite sides of said block and each having openings therein corresponding in size and location to the ends of said screw holes in said block adjacent to said respective contacts, and attaching screws for said contacts.
11. In a signaling mechanism, an insulating block having suitable attaching screw holes therein, signaling contacts mounted 30
- upon the opposite sides of said block, and attaching screws for said contacts, recesses being provided in a side of said block for the heads of the attaching screw or screws of the contact mounted on the opposite side 45 thereof to permit such screw head or heads to be sunk a suitable distance below the surface of said side, and a clearance hole being provided in one contact for the head of each attaching screw of the other contact. 50
12. In a signaling mechanism, an insulating block having suitable attaching screw holes therein, signaling contacts mounted upon the opposite sides of said block, and attaching screws for said contacts, recesses 55 being provided in a side of said block for the heads of the attaching screw or screws of the contact mounted on the opposite side thereof to permit such screw head or heads to be sunk a suitable distance below the surface of said side, and a clearance hole being provided in one contact for the head of each attaching screw of the other contact, a signaling train adapted to suitably operate said contacts, and testing means for said 60 signaling mechanism comprising a movable arm adapted when moved in one direction to separate said contacts independent of the action of said signaling train and when moved in the opposite direction to retain 65 said contacts in engagement regardless of the action of said signaling train.
- In witness whereof, we have hereunto subscribed our names this 18th day of February, A. D., 1915.
